UNITED STATES PATENT OFFICE.

GEORGE W. YOUNG, OF SWAMPSCOTT, MASSACHUSETTS.

SHELF-SUPPORT.

1,038,813.

Specification of Letters Patent. Patented Sept. 17, 1912.

Application filed August 25, 1911. Serial No. 645,957.

To all whom it may concern:

Be it known that I, GEORGE W. YOUNG, a citizen of the United States, residing at Swampscott, in the county of Essex and State of Massachusetts, have invented an Improvement in Shelf-Supports, of which the following is a specification.

This invention relates to shelf-supports, especially adapted for knocked-down shelving.

It has for its object to construct a shelf-support of a pair of upright clamping-members, adapted to engage the front and rear edges of a shelf, and to be drawn toward each other by suitable connecting means to clamp the shelf between them; also, to provide adjustable means for connecting the clamping-members together, whereby they may engage the front and rear edges of shelves of different widths; also, to provide the upright clamping-members with opposing shelf-engaging means at both upper and lower ends thereby to engage the front and rear edges of two shelves, arranged one above the other, the lower shelf serving as a support for the clamping-members; also, to provide clamping-members with shelf-engaging means at its ends made wide enough to engage the front and rear edges of two adjacent shelves, arranged in the same plane, and end to end, and which may abut together; also, more specifically, to provide the clamping-members with rabbeted ends to engage the front and rear edges of the shelves and to connect said members together by suitable means whereby the shelves are clamped between them and thereby firmly held, either the upper ends of the clamping-members or both the upper and lower ends thereof being rabbeted; also, to provide for the employment of one or more bolts as a means for connecting the clamping-members together.

Figure 1 is a front elevation of a shelf-structure comprising a plurality of shelf-supports embodying this invention, and shelves supported by them. Fig. 2 is a side elevation of the shelf-structure shown in Fig. 1. Fig. 3 is an enlarged side elevation of one of the shelf-supports. Fig. 4 is a vertical section of the shelf-support, taken on dotted line 4-4, Fig. 3. Fig. 5 is a side

view of a shelf-support, having modified means for connecting the members thereof together.

55

a, b, represent the two clamping-members of the shelf-support. They are made alike or substantially so, but adapted to be oppositely disposed when in use. They consist of upright bodies of any suitable shape and construction, although, herein shown, as curved in the direction of their length. They have shelf-engaging means at their ends. The upper ends of the clamping-members are here shown as rabbeted at 65 a', b', and when oppositely disposed said rabbeted ends engage the front and rear edges of a shelf and thereby hold it firmly. The recesses formed by rabbeting the upper ends of said members are shallow so that 70 the shoulders a², b², extend upward and overlie the edges of the shelf for short distances only say one half the thickness of the shelf or less. The shoulders are preferably undercut to better enable them to engage the 75 edges of the shelf. The upper ends of the clamping-members are also made wide enough to engage the front and rear edges of two adjacent shelves, see Fig. 4. The means here shown at the upper ends of 80 the clamping-members for engaging the front and rear edges of a shelf, or the front and rear edges of two adjacent shelves, is simple and efficient, but the invention is not limited to the particular construction of 85 shelf-engaging means here shown. The lower ends of the clamping-members are also here shown as rabbeted, at a³, b³, like their upper ends, and said lower rabbeted ends are adapted to engage the front and rear edges 90 of a shelf, or the front and rear edges of two adjacent shelves, said shelf or shelves serving to support the clamping-members. The shelf-engaging means here shown at the lower ends of the clamping-members is also 95 simple and efficient, but in lieu thereof any other means may be employed adapted to engage the front and rear edges of the shelf and suitably support the clamping-members. The two clamping-members are here shown 100 as drawn toward each other to clamp the shelf or shelves between them by one or more bolts c. In Figs. 1 to 4 one bolt is shown and in Fig. 5 three bolts are shown. Said

bolt *c* may be of any suitable length according to the width of the shelf and not only serves as a means for connecting the clamping-members together and for holding them in clamping position, but, being adjustable, provide for engaging shelves of different widths. By curving the bodies of the clamping-members in the direction of their length and arranging the connecting-bolt at the 10 waist a short bolt may be employed. Said bolts may also serve as rests for additional shelves if desired, see Fig. 5, wherein an additional shelf is arranged on the middle bolt.

In lieu of employing bolts as the connecting means for the two upright clamping-members of the shelf-support any other means may be employed having the capability of drawing the two clamping-members toward each other to clamp the shelf 20 between them and to hold them in clamping position.

When assembling a shelf-structure, such for instance as shown in Figs. 1 and 2, a bottom shelf *d* is arranged on a suitable base, then two shelf-supports are arranged 25 on said base, side by side, and a shelf, as *d'*, arranged on said supports, and the shelf-supports are then tightly clamped in engagement with said shelves *d* and *d'*. Then 30 other shelf-supports and shelves are added until the structure is completed. As the shoulders formed by rabbeting the upper and lower ends of the clamping-members extend only a short distance over the edges 35 of the shelves several shelf-supports may be arranged one above the other, in vertical alinement, forming a stack of shelf-supports, and the greatest amount of unobstructed space on the shelves is afforded.

40 The shelf-support embodying this invention provides for the production of a shelf-structure of any desired dimensions, and which may be increased or decreased at will, and the clamping-members of the shelf-supports may be adjusted to compensate for 45 shrinkage of the shelves, so that the shelves will be rigidly held at all times.

I claim:

1. A shelf-structure consisting of two 50 pairs of upright clamping-members, the members of each pair being arranged one in front of the other and having opposing shelf-engaging means at their upper ends to engage, respectively, the front and rear 55 edges of a shelf, and means to connect the members of each pair together and hold them in clamping position, substantially as described.

2. A shelf-structure consisting of two 60 pairs of upright clamping-members, the members of each pair being arranged one in front of the other and having opposing shelf-engaging means at their upper and lower ends to engage the front and rear 65 edges of two shelves, and means to connect

the members of each pair together and hold them in clamping position, substantially as described.

3. A shelf-structure consisting of two pairs of upright clamping-members, the members of each pair being arranged one in front of the other and having opposing shelf-engaging means at their upper ends to engage the front and rear edges of the shelf, and adjustable means to connect the members of each pair together and hold them in clamping position to provide for engaging shelves of different widths, substantially as described. 70

4. A shelf-structure consisting of a pair 80 of upright members adapted to be arranged one in front of the other, said members having opposing rabbeted ends to receive the front and rear edges of a shelf between them, the upright shoulders of said rabbeted ends extending short distances from the edges of the shelf, and means to connect said members together and hold them in clamping position, substantially as described. 85

5. A shelf-support consisting of a pair of upright clamping-members, said members having their upper and lower ends rabbeted to receive a shelf between them, the upright shoulders of said rabbeted ends extending but a short distance over the edge 95 of the shelves, whereby several shelf-supports may be arranged in vertical alinement, and means for connecting said members together and for holding them in clamping 100 position, substantially as described. 90

6. A shelf-support consisting of a pair of upright clamping-members, said members having opposing shelf-engaging means at their upper ends and being curved in a direction toward each other at the waist, and one or more bolts connecting said members at the waist and for holding them in clamping 105 position; substantially as described.

7. A shelf-structure composed of a plurality of pairs of shelf-supports arranged one above the other, each shelf-support comprising a pair of upright clamping-members having their upper and lower ends rabbeted to receive a shelf between them, and 115 means to connect the members of each pair together and hold them in clamping position, substantially as described. 110

8. A shelf-structure composed of a plurality of pairs of shelf-supports, arranged one above the other, each shelf-support comprising a pair of upright members having opposing shelf-engaging means at their upper and lower ends, said shelf-engaging means extending short distances over the 120 edges of the shelves, permitting vertical arrangement of the shelf-supports, substantially as described. 125

9. A shelf-structure composed of a plurality of pairs of shelf-supports, arranged 130

one above the other, each shelf-support comprising a pair of upright members having opposing shelf-engaging means at their upper and lower ends and made wide enough to engage the adjacent ends of two shelves, substantially as described.

In testimony whereof, I have signed my

name to this specification, in the presence of two subscribing witnesses.

GEORGE W. YOUNG.
